UNITED STATES PATENT OFFICE.

ALBERT EDWIN HOLBROOK AND JOHN FRANCIS HARDING, OF
ABERTILLERY, ENGLAND.

AIR-DOOR FOR COAL-MINES.

SPECIFICATION forming part of Letters Patent No. 597,147, dated January 11, 1898.

Application filed June 30, 1897. Serial No. 642,974. (No model.)

To all whom it may concern:

Be it known that we, ALBERT EDWIN HOLBROOK, residing at Holly House, Brynteg, and JOHN FRANCIS HARDING, residing at 33 Castle Street, Abertillery, in the county of Monmouth, England, subjects of the Queen of Great Britain, have invented certain new and useful Improvements Relating to Air-Doors for Coal-Mines and Underground Workings, 10 of which the following is a specification.

This invention consists of improvements relating to air-doors for coal-mines and underground workings, our object being to provide simple and reliable means for effecting the automatic opening and closing of such doors by the movement of a passing wagon or vehicle.

In the accompanying sheet of explanatory drawings, to be hereinafter referred to, Figure 1 is a front elevation of a pair of air-doors arranged in combination with our opening and closing appliances. Fig. 2 is a sectional plan through the line *a b*, Fig. 1, the fixed framing of the doors being represented by dotted lines. Fig. 3 is an end elevation showing the connection between the doors and the operating mechanism. Fig. 4 is a plan showing the endless-cord connection between the pair of doors. Fig. 5 is a front elevation representing a modified arrangement of the operating mechanism.

The same reference-letters in the different views indicate the same parts.

In carrying our invention into effect we employ a weight, such as A, for the purpose of keeping the doors B B' in their closed position, the weight-suspension cord or chain C being connected with one door only, but as the two doors are connected by the endless 35 cord or chain D the rising or falling movement of the weight A will produce a movement of the doors B B' in opposite directions, either toward or away from each other. The door B is connected with the upper end of the lever E, and on the outer ends of the axis or pivot-pin of such lever E we mount the shorter arms or levers F F', which are in turn connected with the levers G G'. Each length of rail H H', adjacent to the door B, is arranged 40 in lateral guides J, and its end remote from the door is attached to its sleeper or bearer by a stud K, Fig. 3, the body of the stud fitting loosely within a hole formed for its re-

ception in the rail. The rails H H' are also connected by a short pitman or rod L L' with 55 the levers G G', and the whole of the levers and connections are so arranged that when the doors are closed the rails H H' are held in the tilted or inclined position illustrated at Fig. 3; but on the approach of a wagon or 60 vehicle on the rails toward either side of the doors the tilted rails will be automatically depressed by the load imposed upon them by the vehicle-wheels, such load being sufficient to raise the counterweight A and to open the 65 doors by means of the connecting-levers E F F' G G' and short pitman or rods L L'. When the wagon or vehicle has passed through the doorway and its wheels are clear of the movable rails, the doors will be closed by the descent of the weight A and the rails again 70 raised to their inclined or tilted position.

The doors are hung by the runners or pulleys M upon the supporting-bar N, fixed to the casing, and they can thus be moved readily 75 under the action of the counterweight A or the force imposed by the passing wagon or vehicle, as described.

Either rail of the pair adjacent to the doors can be made the movable rail and connected 80 with the door-operating mechanism.

The illustration at Fig. 5 represents the rail remote from the lever E arranged as the movable rail. The rail adjacent to the lever is fixed and forms no part of the door-oper- 85 ating mechanism.

Having now described our invention, what we claim as new, and desire to secure by Letters Patent, is—

In combination with the sliding doors, the 90 endless cord connecting them to move in unison in opening and closing, the weight for closing the doors automatically, the lever E connected directly to one gate, the rock-shaft F adjacent to the track and carrying the le- 95 ver, the movable track-section adjacent to the gate and the arm under said section connected to the rock-shaft.

In witness whereof we have hereunto set our hands in presence of two witnesses.

ALBERT EDWIN HOLBROOK.
JOHN FRANCIS HARDING.
